ATTORNEY

UNITED STATES PATENT OFFICE

ROBERT S. BROWN, OF NEW BRITAIN, CONNECTICUT, ASSIGNOR TO THE NEW BRITAIN MACHINE COMPANY, OF NEW BRITAIN, CONNECTICUT, A CORPORATION OF CONNECTICUT

MORTISING MACHINE

Application filed September 11, 1928. Serial No. 305,177.

My invention relates to certain new and useful improvements in wood working machines and especially in so-called "chain" mortising machines.

Among the main objects of my invention are, to provide features of construction by which the mortising work may be rapidly and accurately performed, and by which a lateral as well as a depthwise cut may be made when mortises of greater length than would be produced by a single depthwise cut are desired; also, to provide new and improved features of construction by which the work of operating the machine is greatly simplified and this I accomplish by certain new features of construction by which the operation of the machine is controlled partly by a manual act and partly by the mechanical functioning of the machine itself.

These and other objects will be apparent to the mechanic skilled in this art by a reading of the following description and an examination of the accompanying drawings in which I have shown my invention in only one preferred form and in which drawings—

Fig. 1 is a complete side elevation of a mortising machine made according to the present invention;

Fig. 2 is a side elevation of the machine taken from the opposite side from Fig. 1, parts being shown in section to more clearly disclose their construction;

Fig. 3 is an enlarged side view of a part of the mechanism for raising the work support mounted on the base of the machine;

Fig. 4 is a sectional view taken upon the plane of line 4—4 of Fig. 3;

Fig. 5 is a side elevation of the latch means for retaining the work support in its elevated position;

Fig. 6 is a view similar to Fig. 5 with the parts in a different operative position;

Fig. 7 is a side elevation partly in section of the means for actuating the latch means for holding the work support in an operative position, the parts being shown in the position assumed when the support is in its lower position;

Fig. 8 is a view similar to Fig. 7 with the parts shown in the position assumed when

the support has been moved to its elevated position;

Fig. 9 is a cross sectional view of the upper end of the machine showing the main driving shaft and the chain cutter;

Fig. 10 is a sectional view taken through the dash pot employed in the machine;

Fig. 11 is an isometric view of the clutch actuating member of the feed mechanism;

Figs. 12, 13 and 14 are views of work operated upon by the machine; and

Figs. 15 and 16 are isometric views of the mechanism shown in Figs. 5 and 6.

Fig. 17 is an isometric view of the latch 91 shown in Figs. 4, 7 and 8.

In the drawings, 10 represents a column forming the base and frame of the machine. 11 is a horizontal shaft in the upper part of the column 10 carrying a pulley 13 driven by a belt 12 from any suitable source of power, such as a motor 14, which may be mounted within the column. 15 is a sprocket wheel on the shaft 11 for driving a chain cutter 16. The shaft is preferably supported on antifriction bearings 17—18. 19 is a cone pulley splined on the rear end of shaft 11 for driving the feed mechanism presently to be described. This pulley 19 may be held in place against a spacer 21 by a nut 20 threaded on the end of the shaft which itself may form an additional step to the cone pulley. A lock nut 22 for the nut 20 may be threaded on the end of the shaft 11.

23 are ways on the front of the column 10 on which is vertically movable the saddle part of a work support or carrier 24. 25 represents the usual work table or holder which is suitably constructed for clamping thereon a piece of work which is to be mortised by the chain cutter 16 and which may be manually moved or adjusted laterally in the usual way. The support 24 and the work table carried thereby are supported by means of a nut 27 carried by a screw 26. The nut 27 preferably has a bevel gear 29 and may be rotated by a shaft 30 having a small pinion gear at its inner end meshing with the bevel gear 29. Thereby the nut 27 may be moved on the screw 26 for adjusting the initial position of the work table.

The table itself is moved upwardly by the

feed mechanism that I am about to describe. The screw threaded rod 26 is provided with a rack 31 at its upper end in which meshes a segmental gear 32 on a lever 33 which is pivoted on bearings in the column 10 by the shaft 34. The lever 33 is actuated by means that I shall now describe so as to positively move the rack 31 and the work table upwardly during the mortising operation. The cone pulley 19 by belt 35 drives cone pulley 36 which is on a short horizontal shaft 37 on one side of the column 10. The shaft 37 has a worm 38 engaging a worm wheel 39. The worm wheel 39 is secured to a member 42 rotatably mounted on a horizontal shaft 40 extending from side to side of the column 10. Within the member 42 is pressed a pair of shafts 43 upon each of which is loosely mounted a pair of planetary differential pinions 41. The pinions of each pair are connected to each other and are of slightly different tooth number. One pinion of each pair engages a sun gear 44 fixedly secured to the shaft 40, while the other pinion of each pair engages a sun gear 45 fixedly secured to a sleeve or quill 46 rotatable on the shaft 40. The outer ends of the shafts 43 are supported within a housing ring 42^a. The worm wheel 39, the member 42, and the ring 42^a are suitably held together as by bolts 42^b, one of which is shown in Fig. 4. The shaft 40 is mounted in a housing 49 suitably secured in an opening in the column 10. The parts 49 and 50 form a housing for the worm gear 39, the planetary mechanism, the quill 46, and the shaft 40. Slidable on the shaft 40, but rotatable therewith by reason of flattened engaging portions on the shaft and disks, is one set of disks of a multiple disk brake 47, the other set cooperating therewith being held from rotation by a stationary bolt or stud 48.

The above mechanism forms a differential planetary mechanism which acts as a clutch for transmitting power from the shaft 37 to the quill 46. When the brake disks are forced together, the shaft 40 and the sun gear 44 fixed thereon are held against rotation, and the quill 46 will be slowly driven through the medium of the planetary mechanism. When, however, the brake is released, said shaft 40 and sun gear 44 thereon are free to rotate, and no power will be transmitted to the quill 46 through said planetary mechanism. Part 51 is supported by the column 10 and forms a housing for the brake 47.

The brake 47 is operated as follows: Pivottally mounted on the part 51 is a bell crank lever 52, a part of which is adapted to bear against the outer disk of the brake 47. The outer end of said lever is connected by link 53 to a spool 54 slidably mounted on the outer end of the shaft 40 and operated by a bell crank lever 56 having pins engaging a collar 55 in the groove part of the spool 54. 78 is a yoke fixedly attached to a mov-

able rod 73. The yoke 78 straddles a pin 56^a on the side of the bell crank lever 56 which is pivoted at 59 so that as the rod 73 is moved up and down, the bell crank lever will be operated to in turn apply and release the brake 47. Rod 73 is connected at its lower end to a foot treadle 70 pivoted at 71 to the base of the column 10. 72 is a counterbalance weight adjacent the lower end of the rod 73 serving to normally pull the rod 73 downwardly and elevate the foot treadle 70. When the foot treadle 70 is fully depressed, the rod 73 will be elevated sufficiently to apply the brake 47 and hold the shaft 40 with its sun gear 44 against rotation, thus causing the planetary gear to transmit a rotary movement to the quill 46.

The quill 46 has fixed thereon a pinion 57 which engages a segmental gear 58 on the rear end of the lever 33, the front end of said lever having the aforesaid segmental gear 32 which meshes with the rack 31. When the quill 46 is rotated by the planetary gear, movement will be imparted to the lever 33 in a direction to raise the work table.

If the operator keeps the treadle depressed, the upward feeding of the work table will be automatically stopped at a predetermined upward limit and the table will be retained in that position by means which I shall now describe. On the rod 73 is a collar 74 adjustably fastened by a set screw 75. The position on the rod 73 at which the collar 74 is fastened determines the length of stroke of the work support 24 and hence the depthwise cut of the mortise. The shaft 34 is fixedly attached to the member 33 and carries an arm 77 fixedly attached to its outer end. The arm 77 is pivotally attached to a pivot pin on a sleeve 76 which is slidable on the rod 73. As the work support 24 moves upward the sleeve 76 slides down on the rod 73 oscillating the rod slightly about a pivot 73^a which connects the rod and the treadle 70. When the raising mechanism has operated and the tool has cut the required depth, the sleeve 76 strikes the collar 74 and moves the rod 73 downward a slight distance rocking the bell crank lever 56 and disengaging the brake 47. As the member 33 is being moved by power transmitted through the planetary gear mechanism during the raising of the work support, this slight downward motion of the rod 73 will take place against the pressure of the operator's foot upon the treadle 70.

Automatic means are provided for holding the work support 24 in its elevated position as long as the treadle 70 is depressed. Pawls 80 are pivotally mounted on the housing 49 and have their outer ends suitably pointed to engage the teeth of a ratchet-wheel 81 which may be formed integrally with the quill 46. When engaged with the ratchet-wheel 81, the pawls 80 hold quill 46

from clockwise rotation and prevent the work support 24 from descending. The pawls 80 are made of slightly different length so that one or the other will drop into engaging position with a tooth on ratchet-wheel 81 when counter-clockwise rotation of the ratchet-wheel ceases, without permitting material clockwise movement of the pinion 57 and downward movement of the work support 24.

Means are provided so that when the treadle 70 is released, the pawls 80 will be raised out of engagement with the ratchet-wheel 81 to enable the work support 24 to descend under the influence of its own weight. Journalized in the column 10 is an oscillating shaft 92 to which is rigidly attached a lug 87, a rocker arm 90, and the radially extending weighted member 82. When the operator releases the treadle 70, the yoke 78 is lowered and therewith an extension 88 on said yoke which carries an adjustable screw 89. This screw 89 strikes the rocker arm 90 and throws the weighted member 82 to the right beyond its vertical position, whereupon its continued movement to the right by gravity causes the lug 87 to strike the heels of the pawls 80 and raise them out of engagement with the ratchet-wheel 81. The quill 46 is then free to rotate and the work support 24 will drop under the influence of its own weight.

The fall of the work support is checked by a dash-pot 28 attached to the lower end of the screw threaded rod 26. The dash-pot 28 slides over a hollow piston 61 fixed to the column 10. The head of the hollow piston 61 is provided with an upwardly opening check valve 63 normally closed by a light spring 65. 66 is a cup washer held in place by the part 64. The lower end of the piston has one or more openings 62 provided with a screen 62^a to admit air into the interior of the piston. Air flows freely through the check valve 63 into the space within the dash-pot 28 above the piston when the dash-pot is rising, thus permitting free movement in an upward direction of the rod 26. A vent 68 in the side wall of the dash-pot permits air to escape so as to allow the rod 26 to descend freely to the point where the piston closes said vent. From this point on, air can only escape from the dash-pot through a passage controlled by an adjustable needle valve 67 which may be so restricted by said valve as to provide an air check to slow up the descent of the work table during said period.

A pawl latch in the form of a bell crank lever 84 is pivoted to the frame by means of the pivot 84^a. The horizontal arm of the pawl latch 84 has a notch 85 forming a shoulder which is adapted to engage pins 86 on the pawls 80 when the pawls are raised and thus hold the pawls 80 out of engagement with the

ratchet-wheel during the downward motion of the work support.

An automatic resetting mechanism is provided to automatically reset the weighted member 82 in its left position shown in Fig. 6 and thereby automatically release the pawls from the pawl latch 84 so that they may again function automatically to engage the ratchet-wheel 81 at the end of the next upward stroke of the work support 24 (see Figs. 4 to 8). Fixedly attached to the shaft 92 is a radially extending member 93. A link 83 is pivoted at one end to the member 93 and has a tooth at its opposite end which is adapted to engage with a tooth of the pinion 57 when the pinion 57 ceases rotation at the end of the downward stroke of the work support 24. The position of the link 83 when the work support 24 is at its lowest position is shown in Fig. 7. When the pinion 57 rotates to raise the work support, its coaction with the link 83 will push the link 83 and the weighted member 82 to the left beyond the vertical position of the latter. The weighted member 82 will then fall into its extreme left position (shown in Fig. 8) under the influence of gravity. During the latter part of this motion, a lug 94 on the link 83 will engage with the hub of the member 93 to lift the tooth end of link 83 to the position shown in Fig. 8. 93

When the weighted member 82 reaches its extreme left position, it coacts with an adjustable shoulder 95 on the upwardly extending arm of the pawl latch 84 so as to oscillate the horizontal arm of the pawl latch 84 upward and release the pawls 80 therefrom. The pawls 80 are then free to engage with the ratchet-wheel 81 at the end of the upward stroke of the work support 24.

Suitable automatic means are provided for dropping the tooth end of the link 83 into engagement with a sufficiently remote tooth of the pinion 57 so that a partial rotation of the pinion 57 will suffice to move the weighted member 82 to the left past its vertical position.

In the form shown, this means comprises an arm 91 pivoted at 97 and having a laterally extending lug 98 at its free end which coacts with a pin 99 on the side of the link 83 to prevent the toothed end of the latter from too quickly engaging the pinion 57 when the link is moved from the position indicated in solid lines in Fig. 8 to that indicated in solid lines in Fig. 7. On this movement, the pin 99 rides over the lug 98 as indicated in dotted lines in Fig. 8 with the result that the toothed end of the link 83 engages a remote tooth on the pinion 57. When the weighted arm 82 moves from the position indicated in solid lines in Fig. 7 to that indicated in solid lines in Fig. 8, the pin 99 will pass under the lug 98 as indicated in dotted lines in Fig. 7, the arm 91 momentarily rising to permit the pin to pass. A spring 130

pressed plunger 96 coacts with the arm 91 to yieldingly hold it normally in the position indicated in solid lines in Figs. 7 and 8.

The machine operates as follows:

5 When the treadle 70 is pushed down, the brake 47 is applied, causing the pinion 57 to rotate counter-clockwise and raise the work support 24. The rotation of the pinion 57 will also push the weighted member 82 to the 10 left of the position shown in Fig. 8. The movement of the weighted member 82 to the left will trip the pawl latch 84, releasing the pawls 80 from the pawl latch and permitting the pawls to ratchet upon the ratchet-wheel 15 81, which is rotating as the work support is being raised (see Fig. 6). The length of stroke of the work support, and hence the depthwise cut of the mortise, are controlled by the setting of the collar 74. When the 20 work support has reached the predetermined limit of its upward excursion, the arm 77 operates to move the rod 73 slightly downward against the pressure of the foot upon the treadle 70. This slight motion of the 25 rod 73 oscillates the bell crank lever 56 sufficient to release the brake 47. As soon as the brake is released, the rotation of the ratchet-wheel 81 ceases and the pawls 80 then engage the ratchet-wheel and hold it against reverse 30 rotation, thus retaining the work support 24 in its raised position.

When the operator releases the treadle 70, the counterbalance 72 operates on the rod 73 to move it downward. The downward motion of the rod will release the brake if it has not already been released automatically as just mentioned. As the rod 73 moves downward, the screw 89 coacts with the rocker arm 90 to move the weighted member to 40 the right. The movement of the weighted member to the right produces three separate effects. The first effect is to disengage the pawls 80 from the ratchet-wheel 81 (see Fig. 5), permitting the work support 24 to fall 45 under the influence of its own weight, its fall being checked by the compression of air in the dash-pot 28. The second effect of the movement of the weighted member to the right is to allow the horizontal arm of the 50 pawl latch 84 to fall under the influence of its own weight, with the result that the pawl latch 84 engages with the pawls 80 and holds them out of engagement with the ratchet-wheel 81 during the descent of the work support and until the treadle 70 is pushed down 55 for the next feed stroke of the work support. The third effect of the movement of the weighted member 82 to the right is to move the link 83 to a position where its toothed end 60 will engage with a tooth of the pinion 57 (see Fig. 7) when the rotation of the pinion ceases at the bottom of the stroke of the work support 24. When the brake is again applied and the pinion 57 starts to rotate counter-clockwise as shown in Fig. 7, the weighted

member 82 will be reset in the position shown in Figs. 6 and 8, in the manner previously described.

After two or more adjacent cuts have been made to form a long mortise, the treadle 70 is held down after the last cut, thus keeping the work support 24 in its raised position, and the work holder 25 may then be moved laterally by hand. This lateral movement of the work holder 25 causes the cutter to remove fillets such as shown in Fig. 13 as the end of the cutter travels across the bottom of the mortise. The operator then releases the treadle 70, thus disengaging the pawls 80 from the ratchet-wheel 81 and the work support 24 falls to its lowest position.

I claim:

1. A mortiser comprising in combination, a base, a cutter mounted thereon, a work support movably mounted on said base, a power-driven machine-feed mechanism for said support, means to automatically and positively lock the support in a position with the cutter engaged with the work, and means to release the support for movement from the cutter by gravity.

2. A mortiser comprising in combination, a base, a cutter mounted thereon, a work support movable toward and from said cutter said support being moved away from said cutter by gravity, power-driven machine, feed mechanism for moving the support toward the cutter, automatic means to release said feeding means when said support reaches a predetermined operative position, and automatic means to positively lock said support in said predetermined operative position.

3. A mortiser comprising in combination, a revolvable cutter, a work support, power-driven machine, feed mechanism for moving one of said members toward the other, a treadle for controlling said feed mechanism, means controlled by said treadle to release said feeding means and permit said one member to move downward by gravity, and means to automatically and positively lock said one member in a predetermined operative position.

4. A mortiser comprising in combination, a base, a cutter mounted thereon, a work support movably mounted on said base, feed mechanism for moving said support toward the cutter, a driving pinion for said feed mechanism, a clutch for rotating said pinion, a treadle to operate said clutch, locking means for said driving pinion in one position of said support, and means to release said locking means to permit movement of said support away from said cutter.

5. A mortiser comprising in combination, a base, a cutter mounted thereon, a work support on said base, feed mechanism for relatively moving said cutter and support toward each other, said feed mechanism including a driving pinion, a power-driven differ-

- ential planetary mechanism for operating said pinion, a brake for controlling said planetary mechanism, a treadle to operate said brake, locking means for automatically 5 and positively locking said driving pinion in one position of said support, and means controlled by said treadle to release said locking means to permit relative movement by gravity of said cutter and support away from 10 each other.
6. A mortiser comprising in combination, a base, a cutter mounted thereon, a work support movably mounted on said base, feed mechanism for moving said support toward 15 the cutter, an oscillatory member for moving said support, a pinion engaging gear teeth on said member, and means to rotate said pinion, said means comprising a power-operated differential planetary mechanism controlled by a brake.
7. A mortiser comprising in combination, a base, a cutter mounted thereon, a work support on said base, feed mechanism for relatively moving said cutter and support toward 25 each other, an oscillatory member for moving one of said members on said base, a pinion engaging gear teeth on said oscillatory member, means to rotate said pinion, said means comprising a power-operated differential 30 planetary mechanism, a brake for controlling said mechanism, a treadle to operate said brake, said cutter and said support being separated by gravity, and automatic means for positively locking one of said parts in 35 fixed position relative to the other.
8. Feed mechanism for a work support for a wood working machine comprising in combination, an oscillatory member connected to said support so that oscillation thereof will 40 move said support, a driving pinion connected to said member, means to rotate said pinion in one direction to advance said support toward a cutter, means to release the rotating means for said pinion to permit movement by 45 gravity of said support in the opposite direction, and means to lock said support in operative position.
9. Feed mechanism for a work support for a wood working machine comprising in combination, an oscillatory member connected to said support so that oscillation thereof will move said support, a driving pinion connected to said member, means to rotate said pinion in one direction to advance said support 50 toward a cutter, a clutch in the driving mechanism for said pinion, means to engage and disengage said clutch, and means to retain said support in elevated position with said clutch disengaged.
10. Feed mechanism for a work support for a wood working machine comprising in combination, an oscillatory member connected to said support so that oscillation thereof will move said support, a driving pinion connected to said member, means to ro- 55 tate said pinion in one direction to advance said support toward a cutter, a clutch in the driving mechanism for said pinion, means to engage and disengage said clutch, means to lock said support in elevated position with said clutch disengaged, and means to release 60 said locking means.
11. A mortiser comprising in combination, a base, a cutter mounted thereon, a support movable on said base toward and from said cutter, an oscillatory member, an adjustable connection between said oscillatory member and said support, means to oscillate said member in one direction to move said support toward said cutter, a driving pinion for actuating said oscillatory member, locking means for retaining said pinion and oscillatory member in one position, and means to render said locking means inoperative.
12. A mortiser comprising in combination, a base, a cutter mounted thereon, a support movable on said base toward and from said cutter, a driving pinion operatively connected to said support for effecting movement thereof in one direction, power-driven differential planetary mechanism for rotating said pinion, brake means to control said mechanism, said support being moved by gravity in the opposite direction, and locking means for automatically and positively locking said support in operative position.
13. A mortiser comprising in combination, a base, a cutter mounted thereon, a support movable on said base, an oscillatory member within the base, an adjustable connection between said oscillatory member and said support, power-driven means for actuating said oscillatory member in one direction to move said support toward said cutter, said support being moved away from said cutter by gravity, and locking means for automatically and positively locking said support in operative position.
14. In a machine of the character described, a power-driven revolving cutter and a work support, a power-driven machine-feed mechanism for moving one of said members toward the other, means for automatically and positively locking said one member in position when said one member reaches its point of closest approach toward said other member, and means for releasing said locking means so that said one member will move away from said other member by gravity.
15. A chain mortiser, comprising a power-driven chain cutter and a work support, power-driven machine-feed mechanism for moving one of said members toward the other, means for automatically and positively locking said one member in position when said one member reaches its point of closest approach toward said other member, and means for releasing said locking means so that said one member will move away from said other member by gravity.

16. A mortiser having a movable work support and operating means whereby said support is lifted and dropped, said support being lifted by a power-driven machine-feed mechanism and dropped by gravity, and means to automatically and positively lock said support in its raised position.

17. A mortiser having a movable work support and operating means whereby said support is lifted and dropped, said operating means including an oscillatory lever movable to lift said support and a power-driven pinion engaging with said lever, said support being dropped by gravity, and means to automatically and positively lock said support in its raised position.

18. A mortiser having a movable work support and operating means whereby said support is lifted and dropped, said operating means including an oscillatory lever movable to lift said support and a power-driven pinion engaging with said lever, said support being dropped by gravity, an adjustable connection between said lever and said support, and means to automatically and positively lock said support in its raised position.

19. A mortiser having a movable work support and operating means whereby said support is lifted and dropped, said operating means including an oscillatory lever having a geared segment at each end thereof, the geared segment at one end of said lever meshing with a rack on said work support and the geared segment at the other end of said lever meshing with a power-driven pinion, said support being dropped by gravity, and means to automatically and positively lock said support in its raised position.

20. A mortiser having a movable work support and operating means whereby said support is lifted and dropped, said support being lifted by power-driven machine-feed mechanism and dropped by gravity, a dashpot for checking the fall of said support, and means to automatically and positively lock said support in its raised position.

21. A mortiser having a movable work support and operating means whereby said support is lifted and dropped, said operating means including an oscillatory lever movable to lift said support and a power-driven differential planetary mechanism operable to move said lever, said support being dropped by gravity, and means to automatically and positively lock said support in its raised position.

22. A mortiser having a movable work support and operating means whereby said support is lifted and dropped, said operating means including a power-driven machine-feed mechanism for lifting said support and a mechanism to automatically disengage said feed mechanism from the source of power when said support reaches a predetermined position, said support being dropped

by gravity, and means to automatically and positively lock said support in its raised position.

23. A wood working machine comprising, in combination, a base, a power-driven cutter mounted thereon, a work support movable on said base from and toward said cutter, power-driven machine-feed mechanism for moving said support toward said cutter, said support moving away from said cutter by gravity, automatic locking means to positively lock said support in operative position, means to release said locking means, and automatic means to render said locking means inoperative while said support moves away from said cutter.

24. A wood working machine comprising, in combination, a base, a power-driven cutter mounted thereon, a work support movable on said base from and toward said cutter, power-driven machine-feed mechanism for moving said support toward said cutter, said support moving away from said cutter by gravity, automatic locking means to positively lock said support in operative position, means to release said locking means, automatic means to render said locking means inoperative while said support moves away from said cutter, and automatic means to render said locking means operative when said support moves toward said cutter.

25. A wood working machine, comprising, in combination, a base, a power-driven cutter mounted thereon, a work support movable on said base from and toward said cutter, power-driven machine-feed mechanism for moving said support toward said cutter, said support moving away from said cutter by gravity, automatic locking means to positively lock said support in operative position, means to release said locking means, automatic means to render said locking means inoperative while said support moves away from said cutter, and a weighted member which is moved by said feed mechanism when said support moves toward said cutter and which operates by gravity to render said locking means operative.

26. A wood working machine, comprising, in combination, a base, a power-driven cutter mounted thereon, a work support movable on said base from and toward said cutter, power-driven machine-feed mechanism for moving said support toward said cutter, said support moving away from said cutter by gravity, a ratchet wheel gear-connected to said support, a pawl engaging with said ratchet-wheel at the end of each cut, means for tripping said pawl, and a pawl latch for holding said pawl in its tripped position while said support is moving away from said cutter.

27. A wood working machine comprising, in combination, a base, a power-driven cutter mounted thereon, a work support movable on said base from and toward said cutter,

power-driven machine-feed mechanism for moving said support toward said cutter, said support moving away from said cutter by gravity, a ratchet-wheel gear-connected to said support, a pawl engaging with said ratchet-wheel at the end of each cut, means for tripping said pawl, a pawl latch for holding said pawl in its tripped position while said support is moving away from said cutter, and automatic means for releasing said pawl from said pawl latch when said support moves toward said cutter.

28. A wood working machine comprising, in combination, a base, a power-driven cutter mounted thereon, a support movable on said base from and toward said cutter, a power-driven machine-feed mechanism for moving said support toward said cutter, said support being moved away from said cutter by gravity, a ratchet-wheel gear-connected to said support, a pawl engaging said ratchet-wheel at the end of each cut, means for tripping said pawl, a pawl latch for holding said pawl in its tripped position while said support is moving away from said cutter, and automatic means for releasing said pawl from said pawl latch when said support moves toward said cutter, said automatic means comprising a weighted member which is moved by said feed mechanism when said support moves toward said cutter and which operates by gravity to release said pawl from said pawl latch.
